J. Brown and J. Brown

UNITED STATES PATENT OFFICE.

JAMES CLAYTON, OF SEBAKWE, BABBACOMBE, ENGLAND, ASSIGNOR TO THE VISCOSA COMPANY, OF MARCUS HOOK, PENNSYLVANIA, A CORPORATION OF PENNSYLVANIA.

TRAVERSE MECHANISM.

1,417,454.

Specification of Letters Patent. Patented May 23, 1922.

Application filed October 12, 1920. Serial No. 416,534.

To all whom it may concern:

Be it known that I, JAMES CLAYTON, a subject of the King of Great Britain and Ireland, and a resident of Sebakwe, Babba-
5 combe, county of Devon, England, have invented certain new and useful Improvements in Traverse Mechanism, of which the following is a specification.

My invention relates to apparatus for 10 spinning artificial silk, and particularly to the traverse mechanism for the spinning boxes. The object of my invention is to provide a mechanism which operates without vibration or undue stresses, by reason of the 15 improved arrangement of the parts to secure a balanced load. A second object of my invention is to associate with the mechanism a suitable arrangement for bringing the spinning boxes to position for discharge.

20 In the accompanying drawings—

Fig. 1 is a longitudinal section through portion of an artificial silk spinning frame, to which my invention has been applied in one form;

25 Fig. 2 is a broken section on the line 2—2, Fig. 1, of a driving gear for the traverse bar;

Fig. 3 is a side elevation, partially in section, of a modified form of the lifting cam for the traverse bar;

30 Fig. 4 is a vertical section through the traverse motion showing the lifting cylinder which raises the spinning boxes for discharge thereof; and

Fig. 5 is a section on the line 5—5, Fig. 4.

35 In apparatus of the type shown in my prior Patent No. 1,240,675, September 18, 1917, the filaments of artificial silk, coming from the setting bath over suitable guides or godets, are coiled in spinning boxes rotated 40 at high speed and simultaneously reciprocated vertically to effect the twisting of the filament into a thread, and the coiling of the same into a fiber cake. In the arrangement described in the patent referred to, the spinning boxes are carried on bars extending longitudinally on opposite sides of the main frame, and supported by rocker arms keyed 45 to a longitudinal shaft, which is oscillated to impart the desired traverse motion to the boxes during the building of the fiber cake.

50 While that arrangement is in perfect balance when stationary, I have found that, when put in motion, detrimental stresses occur, and at the moment of reversal of motion a

couple results which gives rise to a jarring 55 action, which necessitates a severe limitation of the length and speed of operation of the machine. The present arrangement is such, on the contrary, that these stresses are practically eliminated. To this end, the spinning boxes are divided into groups to which 60 traverse motion in opposite directions is imparted simultaneously with the result that not only are the weights balanced with respect to each other on opposite sides of the 65 machine, but the strains on the traverse mechanism on each side of the machine are lessened as well as balanced, with the result that the length of the machine as a whole may be greatly increased and the speed 70 of traverse accelerated without detrimental effect or danger of harm to the apparatus.

To illustrate the invention, portion of one end of the frame 5 is shown, it being understood that the arrangement is the same on 75 both sides of the frame. The spinning boxes 6, of which but one is shown, are supported on spindles 7 driven by electric motors 8 which rest on builder bars 9, 9', etc. The usual long builder bar is thus suitably subdivided, each subdivision carrying 80 a group of motors 8 and their associated spindles and spinning boxes. In the form illustrated, six motors and associated parts are carried on each division of the builder 85 bar. The ends of each section of the builder bar are guided in slideways 10 supported by posts 11 resting on one of the main longitudinal 90 12 of the frame. Midway of its length, each builder bar 9, 9', etc. is engaged by a lifting rod 13 passing through a guide 95 sleeve 14 and provided at its lower end with a roller 15, which bears upon the inclined cam 16 of the traverse bar 17. The latter extends the full length of the machine, and 100 alternate lifting cams 16, 16' are reversely arranged so that upon the horizontal reciprocation of the traverse bar 17 alternate spindle groups are oppositely reciprocated in a vertical direction. Thus, upon the movement of the traverse bar 17 to the right, the builder bar 9 is lifted by the running up of the roller 15 on the cam 16, while the adjacent builder bar 9' is lowered by the running down of its roller on the oppositely 105 inclined cam 16' of the traverse bar. It will thus be obvious that the length of the spinning frame may be at least double, since the

strains imposed upon the driving mechanism of the traverse bar are reduced by half, and even by more than half, since the thrust of the weight of the down-coming builder bars impart a thrust to the traverse bar, through the cams, which aids the driving mechanism.

Longitudinal reciprocating motion is imparted to the traverse bar by the spiral cam 18 on the shaft 19 of the worm gear 20 meshing with the worm 21 at the lower end of the shaft 22. The upper end of the latter is also provided with a worm wheel 23, meshing with the worm 24 on the shaft 25 driven by any suitable driver, e. g., a belt 26. The engagement between the traverse shaft 17 and the spiral cam 18 is attained by a roller 27 on the stud 28 passing through one end of the traverse bar and engaging in the peripheral raceway of the spiral cam 18. The stud is extended on the opposite side also of the bar 17 and carries a slide block 30 (Fig. 2) working in the slideway 31 formed in the gear casing 32.

After the fiber cakes have been spun in the boxes 6, it is desirable to raise the latter out of the chambers 33 in which they are vertically reciprocated by the traverse motion during the spinning operation, in order that the boxes may be readily removed from their spindles 7 for unloading the fiber cakes. To this end the traverse bar 17 is supported through rollers 34 at the upper ends of plungers 35 working in pressure cylinders 36.

Upon the admission of pneumatic or hydraulic pressure to the lower ends of the cylinders 36, the plungers are raised, thus lifting the traverse bar 17 vertically. Inasmuch as the builder bars are still supported by the latter, they are all simultaneously raised and the spinning boxes 6 lifted out of, or to a position in the upper portion of, the spinning chambers 33 at which they are accessible for ready removal. A link 37 interposed between the driving cam 18 and the traverse bar 17 permits the latter to be lifted without breaking connection with the cam.

In order to insure the upward movement of the builder bars in unison upon admission of pressure to the cylinders 36, I provide a equalizer shaft 38 carrying gears 39 which mesh with racks 40 formed on the plungers 35. Obviously this rigid interconnection of the several plunger racks through the equalizer shaft 38 insures their simultaneous and equal rise.

In Fig. 3 I have indicated a modified form of lifting cam on the traverse bar 17. The inclined face of the cam, against which the roller 15 bears, is provided at its opposite ends with inclines 41 of lower pitch in order to facilitate the reversal of the traverse motion at opposite ends of the longitudinal stroke of the traverse bar.

Various modifications of construction will

readily occur to those dealing with the problem, and I do not limit my invention to the details illustrated.

I claim—

1. In a machine of the type described, a series of builder bars, spinning devices supported thereon, a horizontally reciprocating traverse bar common to said series of builder bars, and lifting cams fixed on said traverse bar, said cams being shaped to effect the simultaneous rise and fall of independent builder bars in opposite directions. 75

2. In a machine of the type described, a series of builder bars, a group of motors on each bar, a spinning spindle for each motor adapted to support a spinning box, a lifting rod for each builder bar, and a horizontally reciprocating traverse bar having oppositely arranged fixed cams engaging said lifting rods, and means for reciprocating said traverse bar to impart builder motions simultaneously in opposite directions to independent builder bars, for the purpose specified. 80

3. In a machine of the type described, a series of builder bars, spinning devices supported thereon, and a horizontally reciprocating traverse mechanism operatively connected to said builder bars to operate certain of the latter simultaneously in opposite directions, in combination with vertically reciprocating means for lifting all of said builder bars simultaneously on the completion of the spinning operation to facilitate the unloading of the work. 90

4. In a machine of the type described, a series of builder bars, spinning devices supported thereon, and a horizontally reciprocating traverse mechanism operatively connected to said builder bars to operate certain of the latter simultaneously in opposite directions, in combination with vertically reciprocating means for lifting all of said builder bars simultaneously on the completion of the spinning operation to facilitate 100 the unloading of the work, together with means for equalizing the lift of the builder bars to unloading position.

5. In a machine of the type described, a series of builder bars, spinning devices supported thereon, a horizontally reciprocating traverse bar common to said series of builder bars, and lifting cams on said traverse bar, said cams being shaped to effect the simultaneous rise and fall of independent builder bars in opposite directions, in combination with vertically reciprocating means for lifting the traverse bar upon the completion of the spinning operation to raise all of the spinning mechanisms to unloading position. 115

6. In a machine of the type described, a series of horizontal builder bars, spinning devices mounted thereon, a traverse bar substantially parallel to the builder bars, oppositely faced cams fixed on said traverse 120

bar, lifting rods extending from the builder bars toward the traverse bar and bearing on said cams, and means for horizontally reciprocating the traverse bar to vertically reciprocate the builder bars.

7. In a machine of the type described, a series of horizontal builder bars, spinning devices mounted thereon, a traverse bar substantially parallel to the builder bars, op-
10 positely faced cams fixed on said traverse

bar, lifting rods extending from the builder bars toward the traverse bar and bearing on said cams, and means for horizontally reciprocating the traverse bar to vertically reciprocate the builder bars, together with means 15 for raising the traverse bar to lift the builder bars simultaneously to unloading position.

In testimony whereof I have signed my name to this specification.

JAMES CLAYTON.
